UNITED STATES PATENT OFFICE.

MAURICE TAUBER, OF NEW YORK, N. Y.

RIDING-SKIRT.

SPECIFICATION forming part of Letters Patent No. 734,775, dated July 28, 1903.

Application filed March 3, 1903. Serial No. 145,952. (No model.)

To all whom it may concern:

Be it known that I, MAURICE TAUBER, a citizen of the United States, residing in New York, borough of Manhattan, and State of New York, have invented certain new and useful Improvements in Ladies' Riding-Skirts, of which the following is a specification.

This invention relates to an improved riding-skirt for ladies' use in which the skirt is made in two sections—a front and a back section—that are connected by a safety-strip, so that the lady can in case of danger or accident readily separate the sections and jump from the saddle and pommel without being liable to catch by the skirt on the pommel, and the skirt can afterward be closed again for walking after the danger is passed; and for this purpose the invention consists of a lady's riding-skirt which is composed of two sections—a front and a back section—said sections being connected at their front edges by means of a tearable strip provided with hooks and eyes and stitched to the sections at the front meeting edges at the front of the skirt, said tearable strip and detachable hooks and eyes being continued along the slit arranged in the back section where the pommel passes through the openings in the back section, as will be fully described hereinafter and finally pointed out in the claim.

In the accompanying drawings, Figure 1 represents a perspective view showing a lady on horseback wearing my improved riding-skirt. Fig. 2 shows the front and back sections of a riding-skirt cut according to my improvement. Fig. 3 is a side view of a skirt detached. Fig. 4 is a detail perspective view of the safety-strip as attached to the inside of the skirt. Fig. 5 is a detail view of the skirt, the front and rear sections being held together by the safety-strip; and Fig. 6 is a detail view showing the safety-strip and safety hooks and eyes.

Similar characters of reference indicate corresponding parts.

Referring to the drawings, A represents the front section, and B the back section, of my improved riding-skirt for ladies' use. The front section A is made according to the pattern shown at the right-hand side of Fig. 2, and the back section B is provided with the

usual openings b b, through which the forks of the pommel are passed in the usual manner, said openings being connected by a slit b' in the usual well-known manner. The back section B is provided with an elastic strap for the right leg and the lower part of the front section A with an elastic strap for the left foot, by which the skirt is held in position while riding. The skirt so far described is the well-known riding-skirt heretofore in use, and the elastic straps are therefore not shown in the drawings.

My improved safety attachment consists of an easily-tearable strip of cloth that is stitched under the front seam below the front edges of the front and back sections of the skirt, which are not connected, as heretofore, by a seam, but which are arranged abutting each other at the front of the skirt, as shown in Figs. 4 and 5. To the under side of the tearable safety-strip D are applied at the points 1, 2, 3, 4, and 5 safety-hooks d and eyes d', preferably two at each of the points mentioned, as shown in Figs. 4, 5, and 6. The safety-hook d is made so that it is resilient enough to readily release its eye d' when the safety-strip is torn apart and that it will permit rehooking in the eye d' when it is desired to effect a temporary closing of the skirt along the front edge of the same.

In case of danger or accident the lady rider tears the safety-strip D by taking hold either at the upper or lower end of the skirt at the points marked by arrows in Figs. 1 and 3 and tears it either from the upper end downward or from the lower end upward, as most convenient, separating thereby the front section A from the back section B simultaneously with the separating of the double hooks and eyes, so that the entire riding-skirt is open at the front and permits the ready jumping off of the lady from the saddle and clearing of the skirt from the pommel without being caught by the same. This quick parting of the skirt at the front so as to divide it into separate sections prevents in many cases an accident arising from the catching of the skirt on the pommel and the consequent injury of the rider, owing to the impossibility of jumping freely from the saddle.

After the danger is passed the riding-skirt

is closed again in front by the hooks *d* and eyes *d'*, so that the rider can walk home with a closed skirt in the usual manner.

My improved safety riding-skirt is cut in the same manner as an ordinary riding-skirt, so that the front section is longer in front than at the back for covering the feet in riding. When walking, the skirt is taken up by gathering the front part and holding it as in the present riding-skirts.

After an accident the front and back sections, with the torn-apart safety-strip, are connected by the hooks and eyes. A new strip, which is kept in reserve, is stitched to the front seam of the front and back sections, so as to permit again the use of the skirt with the safety attachment. The safety attachment may be applied to the skirt by the habit-maker. By the improved safety attachment 20 many accidents which heretofore turned out dangerous to life and limb can be effectively prevented, as the lady can easily separate the skirt, liberate herself from the saddle and pommel, jump off the saddle, and prevent thereby

the catching of the skirt on the pommel and 25 avoid the accidents consequent thereto.

Having thus described my invention, I claim as new and desire to secure by Letters Patent—

A safety riding-skirt for ladies' use, consisting of a front and a back section connected at their rear edges and having their front edges detachably connected at the front of the skirt, a pommel-opening in the back section, a slit connecting the pommel-opening 30 with the front edge of the back section, a safety-strip applied to the under side of the front edges of the front and back sections and the edges of the slit, and detachably-connected hooks and eyes at intermittent points 35 40 of said safety-strip, substantially as set forth.

In testimony that I claim the foregoing as my invention I have signed my name in presence of two subscribing witnesses.

MAURICE TAUER.
